(57) **CLAIM**

The ornamental design for a lid for a beverage/food container, as shown and described.

DESCRIPTION

FIG. 1 is a perspective view from above of the lid for a beverage/food container;

FIG. 2 is a perspective view from below and behind of the lid for a beverage/food container;

FIG. 3 is a front view of the lid for a beverage/food container;

FIG. 4 is a right side elevation of the lid for a beverage/food container, with the left side elevation being a mirror image of FIG. 4;

FIG. 5 is a back view of the lid for a beverage/food container; FIG. 6 is a view from above of the lid for a beverage/food container;

FIG. 7 is a bottom view of the lid for a beverage/food container;

FIG. 8 is a perspective view from above and to the front showing the lid for a beverage/food container in another context; and,

FIG. 9 is a view similar to FIG. 8 but again showing the lid for a beverage/food container in yet another context.

The broken lines represent portions of the design that form no part of the claim.
